W. H. Tracy Attorney,

UNITED STATES PATENT OFFICE.

OSCAR H. BARDILL, OF MINNEAPOLIS, MINNESOTA.

STORM-SASH FASTENER.

1,273,129.

Specification of Letters Patent. Patented July 23, 1918.

Application filed April 6, 1915, Serial No. 19,517.

Renewed December 11, 1917. Serial No. 206,677.

To all whom it may concern:

Be it known that I, OSCAR H. BARDILL, a citizen of the United States, residing at Minneapolis, in the county of Hennepin and State of Minnesota, have invented certain new and useful Improvements in Storm-Sash Fasteners, of which the following is a specification.

My invention relates to new and useful improvements in sash fasteners, the primary object of my invention being the provision of an improved form of sash fastener for use in securing storm sashes of the type which are swingingly mounted at their upper ends to the upper portion of the window casing.

I am well aware that sash fasteners have been manufactured, capable of securing the sash in fully open position and in a number of intermediate positions, but my object consists more specifically in providing an automatic fastener which can accomplish this and which, at the same time, will be automatically locked in active position.

With these and other objects in view, my invention will be more fully described, illustrated in the accompanying drawings, and then specifically pointed out in the claims which are attached to and form a part of this application.

In the drawings:

Figure 1 is a central vertical sectional view taken through a conventional window casing, the ordinary upper and lower sashes therein and a storm sash, showing the latter in partially open position;

Fig. 2 is a fragmentary sectional view, showing the storm sash locked in fully closed position;

Fig. 3 is a detail perspective view of a retaining device which is secured to the swinging sash and which lockingly engages the sash fastening arm when the sash is closed;

Fig. 4 is a perspective view of various parts of my invention, showing the co-action between such parts;

Fig. 5 is a detail sectional view taken on the line 5—5 of Fig. 4;

Fig. 6 is a perspective view of the arm, a bracket for pivoting the same and the retaining device with part of the arm broken away.

Corresponding and like parts are referred to in the following description and indicated in all the views of the drawings by the same reference characters.

In order to insure a clear and accurate understanding of my invention and its method of operation, I have illustrated my improved sash fastener in connection with a conventional form of window casing 10 having the usual upper and lower sashes 11 and 12. Hingedly connected to the upper portion of the window casing by suitable hinges 13, is an outer or storm sash 14 which may be of the usual or any preferred type and which, in closed position, engages against the upper and lower sills of the window casing and against the outer parting beads 15 thereof.

Secured to the inner faces of the side bars of this storm sash 14, and at any desired point, usually near the lower end, are brackets 16. Each of these brackets, as best shown in Fig. 4 of the drawings, includes a substantially rectangular shaped body portion 17, usually formed of relatively heavy sheet metal, provided with openings 18 to receive screws or other fastening devices and at one side with a laterally directed perforated ear 19. Pivoted to each of the ears 19 by a rivet, bolt or other suitable means 20, is a locking arm 21. Each of these locking arms is made up of a plurality of sections 22, preferably of heavy sheet steel or other suitable and slightly resilient material, these arms being pivotally connected one to the other in such a manner that their ends somewhat overlap.

Referring to Fig. 5 of the drawings, it will be seen that these overlapping ends, adjacent their point of pivotal connection, are struck out to form locking beads 23 which, when the members are brought into alignment with each other, lockingly engage each other to hold the members in such alignment. Furthermore, the lower edge of each of the members 22, making up the locking arms, is provided adjacent its inner end with a transverse notch 24 formed in its lower edge. The inner end of the innermost of the members 22 has its free end laterally bent, as shown at 25, to form a finger piece by means of which it may be readily held.

Each of these locking arms, in all positions of the fastener, extends through a retaining device, indicated as a whole by the numeral 26 and best illustrated in Fig. 4. Each of these retaining devices is formed from a single piece of relatively heavy sheet metal bent medially to provide an attaching body portion 27 having screw receiving

openings 28 by means of which the device may be attached to the inner face of the outer parting bead 15 and to provide a laterally directed wing portion 29. This wing portion is provided with a vertically disposed, longitudinally extending slot 30 which is extended at one side, as shown at 31, at a point intermediate its length. This widened portion of the slot permits the passage of the bent over terminal 25 of the locking arm in first assembling the fastener and the slot 30 is so formed and the retaining member 26 so positioned that by proper flexing of the locking arms at their hinged joints, the locking arms may be moved back and forth through the slot to either close the storm sash or to open it to any desired extent within the limit of the length of the arms. Obviously, this fastener, in addition to the closed position of the sash, admits of as many open positions of the sash as there are hinged members in the arms. In the drawings, I have illustrated locking arms having three members hingedly connected and the sash may, therefore, be either closed, fully opened, one-third opened or two-thirds opened, as preferred. In any of the open positions of the sash, the locking arms are so manipulated as to cause their notches 24 to engage the retaining members at the lower ends of their slots 30. Obviously, as each member of the locking arms is drawn inwardly through its retaining member to close or partially close the storm sash, they may be swung either upwardly or downwardly in parallel relation to the parting beads 15 in order that they may in no way interfere with the opening and closing of the lower sash proper 12 of the window, this being clearly illustrated in Fig. 1 and also in Fig. 2. In fully closed position of the storm sash, the ears 19 of the brackets 16 extend through the slots 30 of the retaining devices 29 and the entire locking arms are swung into parallel relation to the beads. In order to lock the sash in this position, I provide each of the side bars of the storm sash with a retaining device 32, best shown in Fig. 3 of the drawings. This includes an L-shaped body member of heavy sheet metal, one arm of which is perforated to receive a screw 33 by means of which it may be secured to the inner face of the side bar of the storm sash and the other arm of which terminates in a relatively short hook 34 having a throat portion equal in width to the thickness of the members of the locking arms 21. When the storm sash is fully closed, the free ends of the locking arms are sprung inwardly toward each other slightly and then released to position them in the hook portions 34 of the retaining members 32, all portions or members of the locking arms being then in longitudinal alignment with each other and, consequently,

locked against any breaking or hinge movement. Because of the double engagement of the locking arms with their retaining devices 26, due to the engagement of the notches of these arms with the retaining members and also the engagement of the upturned arm members against the inner face of the wing portions 29 of the retaining members when the storm sash is in any position, except fully open position, and the locking engagement between the notches and retaining member and between the winged portion thereof and the laterally bent terminals 25 of the locking arms 29, when the storm sash is in fully open position, it is practically impossible for the sash to be blown loose. 80

It should be noted that inasmuch as the locking arms 21 are resilient, the said arms may be attached to the sash and the retaining members 26 attached to the window casing in such a manner that there is a constant tendency for the arms to spring laterally into the lateral extensions 31 of the slots 30. It will, therefore, be seen that when the arms are moved through the slots 30, until one of their notches is in vertical alinement with the lower end of the slot, the arms may swing laterally into the extensions 31, the notches engaging the lower edges of such extensions instead of the lower edges of the slots proper and the arms being held against upward movement which would free the notches by their engagement with the upper edges of the extensions 31 of the slots. 100 The arms will, therefore, be locked in position until swung laterally against their natural resiliency. 95

It will of course be understood that I do not wish to be limited to the specific details of construction, illustrated and described, as various minor changes, within the scope of the appended claims, may be made at any time, without in the slightest degree departing from the spirit of my invention. 110

Having thus described the invention, what is claimed as new is:

1. A fastener for swinging sashes including an arm adapted to be pivotally connected to the sash and having its lower face notched, and a retaining member adapted to be secured to a window casing and formed with a vertical slot through which the arm is movable, the slot intermediate its height being widened laterally at one side, whereby the arm may spring laterally into the widened portion and be held against such upward movement as would free its notch from the member. 120

2. A fastener for swinging sashes including a bracket adapted for attachment to the sash and having a laterally directed ear, a resilient arm pivoted to the ear and including a plurality of hingedly connected mem- 130

bers, each provided in its lower edge with a notch adjacent that end more remote from the bracket, and a retaining member in the form of an L-shaped plate adapted to be secured to a window casing, one wing of the plate being formed with a slot through which the arm is movable and of a height greater than the width of the arm, the slot intermediate its length being widened lat-

erally, whereby the arm may spring into 10 the widened portion when one of its notches is in vertical alinement.

In testimony whereof I affix my signature in presence of two witnesses.

OSCAR H. BARDILL. [L. s.]
